UNITED STATES PATENT OFFICE

LOUIS W. GENSBURG, OF CHICAGO, ILLINOIS

DESIGN FOR A GAME BOARD

Application filed March 22, 1933. Serial No. 47,546. Term of patent 3½ years.

To all whom it may concern:

Be it known that I, LOUIS W. GENSBURG, a citizen of the United States, residing at Chicago, in the county of Cook and State of Illinois, have invented a new, original, and ornamental Design for a Game Board, of which the following is a specification, reference being had to the accompanying drawing forming part thereof, and in which:

Fig. 1 is a plan view of a game board showing my new design;

Fig. 2 is a side edge view of the same; and
Fig. 3 is an end edge view of the same.

I claim:

The ornamental design for a game board as shown.

LOUIS W. GENSBURG.
